[57] ABSTRACT

Heat exchanger or unit for a heat exchanger for heat exchanging media reacting vigorously at direct contact composed of one tube for a heat transferring medium and one or more tubes for a heat absorbing medium each tube for the heat absorbing medium being externally in heat conductive contact for at least a large part of its length with the tube for the heat transferring medium by means of a channel-shaped recess provided externally in the wall of the tube for the heat transferring medium, each recess forming a location for a tube for the heat absorbing medium, the profile of which location corresponds to the external shape of each tube for the heat absorbing medium, and is carried out in such a way that the tube for the heat absorbing medium is located in this recess for not more than half its circumference.

HEAT EXCHANGER

The invention relates to a heat exchanger or tube-unit for a heat exchanger in particular for applications for heat-exchanging media that react vigorously at direct contact, such as for example in a steam generator operating with liquid sodium and in a heat exchanger in which CO_2 is heated by liquid sodium, this heat exchanger being composed of at least one tube for a heat-transferring medium and at least one tube for a heat-absorbing medium, every tube for the heat-absorbing medium along a large part of its length being externally in heat-conductive contact with a tube for the heat-transferring medium. With media between which heat transfer takes place in general there is one medium with a relatively low pressure and one medium with a relatively high pressure. It is known from the literature on this subject that for the exchange of heat liquid sodium can be applied as heat-transferring medium to produce steam. Because sodium and water react vigorously at mutual contact the heat exchange between these two media necessitates special safety measures.

To prevent such a sodium-water reaction, with a well-known fast reactor both the water and the sodium are carried through separate tubes, when from a number of these tubes, entirely separated from each other, a heat exchanger is formed with the aid of laminations of heat-conductive material placed against each other, those laminations forming a block in which the tubes are provided, and having mutually externally heat-conductive contact.

Such a construction, however, is rather complicated and expensive from a constructional point of view.

Besides, because in this construction the tubes so to speak are embedded in the laminations, in the event of leakage, in one of the tubes, egressing sodium or steam will put the heat exchanger under pressure because these media cannot escape, causing the heat exchanger easily to be damaged or destroyed.

Another drawback of this construction is that in the event of leakage of one or more tubes it is very difficult, if not impossible, to detect this leakage.

Still another drawback of this construction is that in the event of repair or replacement of one of the tubes the entire heat exchanger will have to be dismounted.

It is the primary object of the invention to exclude a reaction between the two media in a heat exchanger in particular sodium and water or sodium and CO_2 and it is another object of the invention to provide a heat exchanger that does not possess the above drawbacks, is simple to construct, in case of leakage the egressing medium being able to escape easily, and further a leakage being easily detectable, and the tubes being simply dismountable and replaceable.

For that purpose the heat exchanger according to the invention is characterized in that every tube for the heat-transferring medium externally is provided with at least one channel-shaped recess, against which lies a tube for the heat-absorbing medium and the profile of which in the location where the tubes are lying against each other corresponds to the external shape of the tube for the heat-absorbing medium.

As a result of the above arrangement of the individual tubes a heat exchanger is obtained in which on the one hand there is always a double wall between the heat-exchanging media, and in which on the other a di-

rectly heat-transferring contact between the tubes is obtained.

According to the invention the channel-shaped recess is carried out in such a way that the tube for the heat-absorbing medium lying in that recess, is taken into it for not more than half its circumference in order to obtain sufficient free surface of tube wall to allow, if necessary, one of the media to escape and to facilitate the leakage detection.

10 In order to keep the dimensions of the heat exchanger according to the invention as restricted as possible, in the tube for the heat-transferring medium preferably several channel-shaped recesses will be provided.

15 In this way there will be created between the tubes an intensive heat-transferring contact along a large part of the surfaces of the two wall tubes.

20 In order to increase the heat transfer in this respect it may be of advantage to apply into the channel-shaped recesses at the location where the tube walls of the two media are lying against each other, between these two walls, an adequately heat-conductive lute of a mechanical strength slight in respect of the tube walls. For this purpose a two-component lute could be used composed of graphite for the thermal conductivity and of water glass for rendering mechanical strength.

30 In the event of leakage in one of the tube walls another tube wall will always remain between the two media to prevent a sodium-water reaction. Moreover, in the heat-exchanger according to the invention the medium egressing as a result of this leakage will be allowed to escape in a simple way. In case such a leakage occurs in the contact surface between the tubes the one of the tubes may locally be deformed or even may get loose without causing a damage elsewhere in the heat exchanger.

35 As the tubes as such further are not secluded a leakage, if any, is easy to detect and replacement of the tubes is simple. Due to the above safeguarding of the heat exchanger according to the invention radio-active sodium from the primary cooling-circuit of the reactor can also be used as heat-transferring medium with water and steam as heat-absorbing media.

40 This offers the advantage that an intermediate circuit operating with non-radioactive liquid sodium can be dispensed with.

45 By preference, in the tubes a heat-exchange according to the counterflow principle will be applied.

50 Hereinafter the invention will further be elucidated with reference to embodiments of a heat exchanger operating with liquid sodium, given in the drawing:

55 FIGS. 1, 2 and 3 herewith each give in cross-section embodiments with a central tube for feeding through sodium, the water tubes or steam tubes being distributed evenly over the outer wall of this tube.

60 FIG. 4 gives a view and FIG. 5 a cross-sectional view of another embodiment, in which a wide tube, rectangular in section, is applied for feeding through sodium, at the broad sides of which tube the water tubes or the steam tubes are transversely provided in the shape of a pipe coil.

65 In FIGS. 1, 2 and 3, the sodium tube is 1, with provided in the tube walls channel-shaped recesses 2, for forming locations for the water tubes or steam tubes 3.

In FIGS. 1 and 2 the entire tube wall is profiled for shaping these channel-shaped recesses, whereas in FIG. 3 the tube wall is thicker and the channel-shaped recesses are only provided in the outer wall.

The channel-shaped recesses in the sodium tube have such a shape - that the water tubes or steam tubes are taken into these recesses for not more than half their circumferences in order to retain both at the sodium-side and the steam side sufficient tube surface to allow sodium — or steam — to escape and to facilitate leakage detection.

In the embodiments according to FIGS. 1, 2 and 3 the sodium and the steam are fed through the respective tubes in counterflow.

In FIGS. 4 and 5 the sodium tube is a wide flat rectangular tube 1, channel-shaped recesses 2 being provided in the broad walls 4 of the tube in a direction perpendicular to the direction of flow of the sodium through tube 1.

In these channel-shaped recesses 2 the water tubes or steam tubes are provided in the shape of a pipe coil 3.

I claim:

1. A tube assembly for a heat exchanger adapted for media which react violently upon direct contact comprising a large tube provided with at least one external

channel-shaped depression therein and at least one smaller tube which for a large part of its length is disposed with at most half of its circumference in the said channel-shaped depression in the large tube whose profile corresponds to the external shape of the smaller tube, the smaller tube being secured in the depression in the larger tube with means resulting in good thermal contact between the corresponding parts of the two tube surfaces and in only a slight strength of the connection as compared with the strength of the tube walls.

2. A tube assembly as claimed in claim 1, wherein the two tubes are secured together solely by an adhesive located between a substantial part of the two corresponding tube surfaces, the said adhesive forming a connection which has good heat conductivity and whose mechanical strength is slight as compared with the strength of the tube material.

3. Heat exchanger according to claim 1, wherein the tube for the heat-transferring medium has several channel-shaped recesses, which are evenly distributed over the circumference.

4. Heat exchanger according to claim 1, wherein every channel-shaped recess is provided in a direction practically parallel to the centre line of the tube.
